(57) **CLAIM**

The ornamental design for an anal device, as shown and described.

DESCRIPTION

FIG. 1 is a perspective view of an anal device in accordance with the present design;

FIG. 2 is an inverted perspective view thereof;

FIG. 3 is a perspective left side view thereof;

FIG. 4 is a perspective right side view thereof;

FIG. 5 is a top plan view thereof;

FIG. 6 is a bottom view thereof;

FIG. 7 is a front elevation view thereof;

FIG. 8 is a rear elevation view thereof;

FIG. 9 is a right side elevation view thereof; and,

FIG. 10 is a left side elevation view thereof.

The features shown in broken lines depict environmental subject matter only and form no part of the claimed design.

1 Claim, 9 Drawing Sheets
